UNITED STATES PATENT OFFICE.

CARL ALBERT HIRTH, OF CANNSTATT, NEAR STUTTGART, GERMANY.

FEED DEVICE FOR GRINDING-MACHINES FOR BALL-BEARINGS.

1,055,043.

Specification of Letters Patent.

Patented Mar. 4, 1913.

Application filed October 19, 1911. Serial No. 655,624.

To all whom it may concern:

Be it known that I, CARL ALBERT HIRTH, a citizen of the German Empire, and residing in Cannstatt, near Stuttgart, in the Kingdom of Wurttemberg, in the Empire of Germany, have invented certain new and useful Improvements in Feed Devices for Grinding-Machines for Ball-Bearings, of which the following is a specification.

10 In the grinding of balls for ball bearings by means of ball grinding machines having a number of grinding rills, or grooves, an increase in efficiency is obtained by feeding the balls to be ground at a velocity corresponding to that of the grinding disk or surface, instead of at a smaller velocity as used in the past.

15 The invention relates to feed means for ball grinding machines, and has for its object to provide means whereby the balls to be ground are fed at a high velocity to the grinding machines, and also to prevent one ball being thrust against the other and thereby impair the trueness of the same.

20 For this purpose my invention consists of improved means for feeding balls to ball grinding machines, comprising an injector in the path of the balls to be fed, and forcing by the injector action each ball separately against and toward the grinding disks, the fluid, as oil, gas, or air, used for the injector action, serving to form a layer between the individual balls and act as a buffer to the same.

25 In the accompanying drawing, the figure shows a vertical, axial section of my improved device as applied to a guiding means of well known construction.

30 Referring to the drawing, the feed or guiding means *i* is supplied with balls *h* for ball bearing purposes, and seats on a member *m*, which is provided with a lateral tube *n*, which is adapted to feed any suitable fluid, as air, gas, oil, etc., which fluid is under pressure. The guiding means *i* has secured thereto and supported thereby a central guide tube *d* which has its lowest end tapering, as shown by *r*, and this guide tube *d* serves to guide the balls from the guide

member *i*. Contiguous with the tapering end *r* of the guide tube *d* a member *s* is provided which is suitably supported in position so that its tapering bore *t* serves as a guide for the fluid entering the tube *n*. The tapering bore *t*, being arranged much like the well known injector, serves to give the fluid fed through the tube *n* a constantly increasing velocity. The space between the lowest end of the tapering bore *d* and the tapering bore *t* is such as to cause the rapidly moving fluid to draw from the tube *d*, the balls and force them forwardly into the guide or feed tube *a* at substantially the same velocity as that of the fluid.

35 The arrangement described permits a high velocity of the balls to be obtained by a very simple and by comparatively little space. An especially advantageous feature is that layers of fluid are provided, which act like buffers or cushions and prevent an injurious contact of the balls.

40 As a serviceable fluid, not alone gas or steam may be used, but also air or oils, or any fluid acting to cause an injector action, and serve as a means for preventing the balls from being forcibly impinged against each other.

45 Having thus described my invention, I claim as new and desire to secure by Letters Patent:

1. A feed device for ball grinding machines, comprising a guide tube for the balls, a member having a tapering bore for guiding the balls, and means drawing the balls out of the guide tube by an injector action.

50 2. In combination with a feed member, a guide tube supported thereby, having a tapering lower end, a member having a tapering bore surrounding the tapering end of the guide tube, a feed tube at the lower end of the tapering bore, and means for forcing fluid between the wall of the tapering bore and the tapering end of the guide tube for imparting to the balls drawn out of the guide tube and conducted to the feed tube, a velocity substantially equal to that of the fluid.

3. A feed-device for ball-grinding machines, comprising means for guiding a plurality of balls, and injector-acting means adapted to receive said balls from said 5 guiding means and impart velocity thereto.

4. A feed-device for ball-grinding machines, comprising means for guiding a plurality of balls spaced apart, and means for confining a layer of fluid between the sepa-

rated balls, which layer acts as a cushion to therebetween.

In testimony, that I claim the foregoing as my invention, I have signed my name in presence of two subscribing witnesses.

CARL ALBERT HIRTH.
